UNITED STATES PATENT OFFICE.

RUSSELL D. COOK, OF SALT LAKE CITY, UTAH.

BURIAL CASKET.

Application filed May 4, 1922. Serial No. 558,333.

To all whom it may concern:

Be it known that I, RUSSELL D. COOK, a citizen of the United States, residing at Salt Lake City, in the county of Salt Lake and State of Utah, have invented certain new and useful Improvements in Burial Caskets; and I do declare the following to be a full, clear, and exact description of the invention, such as will enable others skilled in the art 10 to which it appertains to make and use the same.

This invention relates to an improved burial casket, and it has for its principal object to provide one which is composed of 15 a comparatively cheap wooden box in which the body is placed, said box being placed within a shell or sham provided with a unique means for connecting the shell and box together, this means being such in construction that it is capable of being manually operated for releasing the shell from the box from the exterior of the crypt independently of the lowering straps and devices ordinarily used.

20 More specifically speaking, it is another object of the invention to generally improve upon caskets of this class by providing one which embodies practical, simple and inexpensive means for temporarily 25 maintaining an attractive shell on the wooden box in which the body is placed.

Other objects and advantages of the invention will be apparent during the course of the following description.

30 In the accompanying drawings forming a part of this specification and in which like numerals are employed to designate like parts throughout the same:

Figure 1 is a side elevational view of a 35 burial casket constructed in accordance with this invention.

Figure 2 is a top plan view thereof.

Figure 3 is a central vertical longitudinal section.

40 Figure 4 is an enlarged detail top plan view of one of the connecting devices between the shell and the box.

Figure 5 is an enlarged detail view with parts in elevation and section showing the 45 construction of one of the connecting devices more clearly.

Figures 6 and 7 are sections taken on the lines 6—6 and 7—7 respectively of Figure 5.

Figure 8 is a detail elevation of one of 50 the anti-friction rollers.

Figure 9 is a vertical section taken on the line 9—9 of Figure 8.

In the drawings, the numeral 1 designates an elongated wooden box which when in use, will be artistically and neatly lined and will have its exterior highly polished. As before indicated, this box is placed within what may be conveniently termed a shell 2 which has its bottom open to permit removal of the box. The surface of this shell or sham 55 as it may be sometimes called, is intended to be covered with a cloth and is to resemble the types of caskets now commonly used.

The idea of placing a box or the like temporarily within a shell of the type specified 60 is, of course, not new and as hereinbefore inferred, the novelty of the invention resides in the employment of practical and unique means for temporarily connecting the box and shell together to permit the latter to be 65 removed from the box and withdrawn from the crypt after interment. Although the means under consideration could be of some other construction, it preferably comprises 70 a plurality of devices mounted on the opposed sides of the shell, each device embodying a vertically disposed flat-faced rod 75 75 which extends through a bore 4 which is formed in the side wall of the shell and opens through the upper and lower edges 80 thereof. At its lower end, the bore opens into relatively small and large recesses 5 and 6 respectively. The first named recess 5 serves to accommodate and permit retraction of the small right angularly disposed 85 supporting plate 7 of the lower end of this rod while the remaining recess 6 has an anchoring plate positioned therein and held in place by suitable fastenings. This plate 8 is formed at its center with an opening in 90 which the reduced journal 9 on the lower end of the rod 3 is rotatable. A bracket 10 is secured to the inner face of the wall of the shell adjacent the upper edge thereof 95 and this bracket is formed with a guide 11 100 arranged in the aforesaid bore to permit passage of the upper end of the rotary rod therethrough. The last named end of the rod is disposed to permit use of a suitable tool for imparting rotation to the rod from 105 the exterior of the crypt. Any desired number of these retaining devices may be employed, there being four of them shown in the drawings, and two being mounted on 110 each opposed side wall of the shell.

Although it may not be essential, I prefer in practice to place suitable means between the shell and box to prevent the latter from binding therein when it is desired to release and remove the shell from the crypt. The means shown comprises a plurality of plates 12 secured to the ends and side walls of the shell, there being anti-friction rollers 13 mounted on these plates to bear against the sides of the box and to prevent binding of the latter.

In practice, the box 1 will be sold by a mortician, the same being highly polished on its exterior and delicately and attractively lined with the desired kinds of material. The sham or shell will be placed around the box as disclosed in the drawings. This shell being only temporary, can be hired by the mortician to the purchaser of the box for a comparatively small charge and when in place it will give the casket the general appearance of those now in use. When the parts are assembled, the supporting plates 7 extend beneath the bottom of the box 1 and serve to detachably and temporarily connect the box and shell together. When the casket is moved from the house and placed in the crypt and after the usual religious services are concluded, a suitable long handled tool with a socket on the end will be used for engaging and imparting rotation to the several bars 3 to retract or swing the supporting plates 7 into the recesses 5, thus permitting the shell to be removed from the inner box and withdrawn from the grave for further use. It is to be noted the connecting devices are manually released at the desired time and do not in any way coact with the usual lowering straps or devices.

From the foregoing description it is obvious that I have devised a novel type of burial casket which is particularly desirable for use by persons not in good financial condition. A casket of this type can be furnished and the entire funeral completed for less than one half of the existing costs. Hence, the main feature of the invention is clearly apparent. Furthermore, the type of casket herein described is practical and desirable over those now patented and marketed and generally resembling an invention of this class. The box and shell are securely held together and can be readily released. However, there is little or no liability of accidental separation of these parts. Other features and advantages of the invention have doubtless been made apparent from the foregoing description and drawings. Therefore, a more lengthy description is thought unnecessary.

Since probably the best results may be obtained with the construction and arrangement herein shown and described, this is taken as the preferred embodiment of the

invention. However, I wish it to be understood that minor changes coming within the scope of the invention as claimed may be resorted to if desired. For instance, it is to be understood that both the box 1, and the sham 2, may be provided with suitable covers or lids.

I claim:

1. A burial casket comprising an open bottom shell having rigid relatively immovable sides, a box for containing the deceased arranged inside of the shell and removable through said bottom, and co-acting means between the shell and the box for detachably connecting the latter with the former, said means being manually operated independent of the usual lowering straps or device from the exterior of the crypt.

2. In a burial casket of the type specified, means for connecting the box with the shell to permit disconnection of the former from the latter when lowered into the crypt, said means comprising a plurality of rods adapted to be rotatably mounted on the sides of the shell, and right-angularly disposed latches carried by the rods and designed to extend beneath and engage the bottom of the box.

3. In a burial casket of the type specified, means for connecting the box with the shell to permit separation of the box from the shell when the casket is lowered into the crypt, said connecting means comprising a plurality of rods adapted to extend vertically and crosswise of the sides of the shell, said rods having their upper ends exposed and flattened to permit use of a tool for turning them, and means on the lower ends of the rods for engaging the box, said means being disengaged from the box when the rods are rotated.

4. In a casket of the type specified, a shell having bores formed in its sides and opening through the upper and lower longitudinal edges thereof, flat-faced rods arranged in said bores and having their ends extending through the ends of the latter, means secured to the sides of said shell for rotatably mounting said rods, and lateral extensions carried by said rods for engaging the body carrier which is placed within said shell.

5. In a casket of the type specified, an outside removable shell, rods rotatably mounted on the opposed sides of said shell, the upper ends of said rods being flat-faced and exposed to permit engagement of tool therewith for rotating them, and right angularly disposed supporting members carried by said rods and engageable with the inner body carrier.

6. The structure set forth in claim 5, the sides of said shell being formed with the recesses into which said supporting members are designed to swing to disengage them from the carrier and to permit the latter to

be removed through the open bottom of the shell.

7. A burial casket including an outside shell, the sides of which are formed with vertical bores opening through the upper and lower edges of said sides, brackets secured to said sides and having guides positioned in said bores, flat-faced rods arranged in said bores and extending rotatably through said guides, the sides of said shell adjacent the

lower edges being formed with upper and lower recesses, plates arranged in the lower recess and having bearing openings, said rods being provided with journals rotatable in said bearings and right angularly disposed supporting plates carried by said rods and receivable in the upper recesses. 15

In testimony whereof I have hereunto set my hand.

RUSSELL D. COOK.
